SPINDLE DRIVING MEANS FOR TEXTILE MACHINES

William R. Gordon, Stonington, Conn., assignor to The Atwood Machine Company, Stonington, Conn., a corporation of New Jersey

Application August 8, 1938, Serial No. 223,578

4 Claims. (Cl. 57—105)

This invention relates to textile machines and particularly to a spinning or twisting machine having driving means for a large number of spindles by a single motor driven belt extending the length of the machine.

An object of the invention is to provide an improved continuously acting take-up or tensioning means for the spindle driving belt to maintain the tension therein uniformly constant at all times during operation of the machine.

Another object of the invention is to provide conveniently accessible means to adjust the tension of the belt during operation if necessary.

And finally it is an object of the invention to provide a motor and driving pulley for the belt upon a carriage mounted at one end of the machine for movement in a direction to vary the tension in the spindle driving belt.

A feature of importance of the invention is that the motor carriage is constantly spring pressed in a direction and with sufficient pressure to maintain proper driving contact between the belt and the spindles.

Another feature of importance is that the carriage supporting the driving motor and pulley is mounted upon suitable grooved wheels movable upon laterally spaced rods extending horizontally and longitudinally of the machine at one end.

And another feature of the invention that is advantageous is that a pair of helical springs fastened at one end to the machine end frame are attached at their opposite ends to a plate threadedly connected to a rod the opposite end of which abuts against an end surface of the motor carriage so that by turning the rod the plate is moved toward or away from the end frame and the tension of the springs is varied.

With the above and other objects in view the invention may include the features of construction and operation set forth in the following specification and illustrated in the accompanying drawings.

In the accompanying drawings annexed here-to and forming a part of this specification, I have shown the invention embodied in a textile doubling and twisting machine of standard form but it will be understood that the invention can be otherwise embodied and that the drawings are not to be construed as defining or limiting the scope of the invention, the claims appended to this specification being relied upon for that purpose.

In the drawings:

Fig. 1 is a plan view of an end portion of a

textile machine to which the invention has been applied;

Fig. 2 is a front elevation partly in section of the parts substantially as shown in Fig. 1, and

Fig. 3 is a side elevation of one of the details of construction.

In the above mentioned drawings there has been shown but one embodiment of the invention which is now deemed preferable, but it is to be understood that changes and modifications may be made within the scope of the appended claims without departing from the spirit of the invention.

Briefly, and in its preferred aspect, the invention may include the following principal parts: First, an end frame forming part of the textile machine; second, a motor supporting carriage movable along a guideway fastened to the end frame; third, a rod or arm attached at one end to the motor carriage and extending longitudinally of the machine, a portion of this rod being threaded; fourth, a cross arm supported on the rod and engaging the screw threads on the inner or free end thereof; fifth, springs attached at one end to the cross arm and at their opposite ends attached to brackets secured to the end frame of the machine; and sixth, means to rotate the arm or rod to vary the position of the cross arm and the tension of said springs.

Referring more in detail to the figures of the drawings there is shown at 10 a motor supporting frame spaced from an end frame 9 of a textile machine and attached thereto by means of bracket members 11 attached to the machine and to the end frame. Two of these brackets are provided having along their upper edges guideways extending horizontally and longitudinally of the machine. Preferably these guideways may be in the form of rods 12 held in position by their ends passing through openings within the brackets 11.

Mounted for movement upon these rods 12 is a carriage 13 having rollers 14 resting upon the rods 12. As shown in Fig. 1 three of these rollers 14 are provided, two upon one side of the carriage 13 and one upon the opposite side. If desired, however, a pair of rollers 14 may be mounted on each guideway 12. Each roller 14 may be centrally grooved upon its periphery and provided with an anti-friction bearing for mounting upon outstanding studs 15 on the carriage 13. Bolted or otherwise secured to the carriage 13 is a motor 16 the armature shaft 17 of which extends vertically and has secured thereto at its upper end a pulley 18. A plate 19

- secured to opposite sides of the carriage 13 as by bolts 20 completely covers and guards the pulley 18. The brackets 11 and the rods 12 are sufficiently long to permit a substantial travel of the carriage 13 along the rods 12 toward and away from the end of the machine upon wheels 14 with minimum friction.
- Extending from the carriage 13 longitudinally of and along a portion of the machine is an elongated rod or tube 21 one end of which engages over an outwardly extending projection 22 formed on the carriage 13. The opposite or free end of the rod 21 is provided with screw threads 23 engaged by internal threads formed in a cross arm 24. The cross arm 24 is held against rotation by a recessed depending portion engaging over a rib 25 formed in a bracket 26 secured to one of the intermediate cross frames 27 of the machine. Extending between the end frame 9 and the cross arm 24 are tension springs 28, two of these springs being shown, one on each side of the threaded or tube rod 21. At one of their ends the springs 28 are attached to the cross arm 24 and at their opposite ends to small brackets 29 attached to the end frame 9. The springs 28 are as shown helically wound tension springs normally stretched as shown in Fig. 1 and forcing the rod 21 and carriage 13 toward the right as seen in the drawings.
- Extending around the pulley 18 is a belt 30 extending the length of the machine and passing around an idler pulley (not shown) at the opposite end of the machine. Disposed along the machine on opposite sides are spindle brackets 31 secured in properly spaced relation to each other on frame girts 32. Each bracket 31 and its mounting has a spindle 33 the whirl 34 of which presses against a surface of the belt 30 during operation. As the spindles 33 and their mountings and operation form no part of the present invention further description of their construction and operation will not be required. As shown in the drawings the spindles 33 are on the outside of the lengths of the belt 30 on each side of the machine and but one spindle on each side is shown. Mounted adjacent the spindles 33 and bearing against the inner surface of the belt are idlers 35 suitably mounted for rotation in positions to properly support the belt 30 against the whirls 34.
- In operation and after the belt 30 has been placed in position upon the machine and around the pulley 18 the rod 21 is rotated by a suitable wrench engaging the hexagon end thereof 36 in a direction to move the cross arm 24 toward the left until the proper compression is exerted upon the rod 21 to give the desired tension to the springs 28. This adjustment forces the carriage 13 toward the right and is constantly exerted.
- By adjusting the tension in springs 28 by rota-

tion of rod 21 to move the cross arm 24 toward or from the end frame 9, any desired tension may be imparted to the belt to give the necessary driving effect to the whirls 34.

I claim as my invention:

1. A textile machine comprising in combination, a frame, a plurality of spindles rotatably mounted thereon, a driving belt for said spindles in contact therewith, a driving pulley for said belt, a motor therefor, a carriage supporting said motor and pulley mounted for movement toward and from said frame, a rod engaging said carriage at one end and extending in the plane of said belt, a cross arm adjustably secured to the rod at its opposite end, and springs secured to said frame and to said cross arm whereby said carriage may be forced by said springs to maintain tension in said belt.

2. A textile machine comprising in combination, a frame, a plurality of spindles rotatably mounted thereon, a driving belt for said spindles in contact therewith, a driving pulley for said belt, a motor therefor, a carriage supporting said motor, guideways on said frame for said carriage extending in the plane of said belt, a rod bearing at one end against said carriage and having a cross arm mounted for longitudinal adjustment thereon, and tension springs extending in the plane of said belt and acting upon said carriage and forcing said carriage in a direction to maintain said belt under spindle driving tension, said springs being attached at one end to said frame and at their opposite ends to said cross arm.

3. A textile machine comprising in combination, a frame, a plurality of spindles rotatably mounted thereon, a driving belt for said spindles, a carriage having a motor thereon and mounted for movement toward and from said frame, a guideway on said frame on which said carriage is movable, driving connections between said motor and belt, a rod engaging and extending from said carriage, and tension springs attached to said machine and adjustably connected to said rod for forcing said carriage in a direction to maintain said belt under predetermined adjustable driving tension, said rod and springs extending parallel to each other and disposed on the plane of said belt.

4. A textile machine comprising in combination, a frame, a plurality of spindles rotatably mounted thereon, a driving belt for said spindles, a carriage having a motor thereon mounted for movement toward and from said frame, a guideway on said frame on which said carriage is movable, driving connections between said motor and belt, a rod engaging and extending from said carriage, springs connected to said rod and frame at their opposite ends, and means to adjust the tension of said springs.

WILLIAM R. GORDON. 60
